UNITED STATES PATENT OFFICE

SIDNEY J. FINN, OF BEVERLY, MASSACHUSETTS, ASSIGNOR TO UNITED SHOE MACHINERY CORPORATION, OF PATERSON, NEW JERSEY, A CORPORATION OF NEW JERSEY

SHOE SUPPORT

Application filed February 16, 1931. Serial No. 516,035.

This invention relates to shoe supports, and more particularly to means for supporting shoes at the top of the forepart. The invention is herein illustrated as embodied in a forepart support or toe rest forming a part of a bed-lasting machine, but it is to be understood that the invention is not thus limited in its applicability.

In supporting a shoe at the top of the forepart, especially at the toe end, it is desirable that the pressure of the shoe support on the upper be distributed as evenly as possible over a considerable portion of the area of the upper, so as to avoid danger of damaging the upper by excessive pressure in any location. It has accordingly been proposed heretofore to utilize in a forepart support a flexible fluid container which conforms itself to the contour of the shoe while substantially equalizing the pressures applied in different locations, as disclosed, for example, in Letters Patent No. 1,495,163, granted on May 27, 1924 upon an application of L. A. Casgrain. An object of the present invention is to provide an improvement in shoe supports of this type, and especially to provide a support having a fluid container which is as flexible as possible and yet is confined in such manner as to prevent excessive expansion thereof in any location under the pressure of the shoe thereon. To this and other ends, the construction herein shown comprises a rubber fluid container mounted in a holder which incloses portions thereof, and a flexible cover of substantially non-elastic material inclosing portions of the container that are outside of the holder and so controlled as to prevent undue expansion of any portion of the container located between the shoe and the holder. More particularly, as illustrated, the flexible cover, which is preferably made of leather, is fitted to serve as a cap loosely mounted over the top and portions of the sides of the container with its marginal portion extending into the holder in position to be clamped against the holder by pressure of the fluid in the container. The marginal portion of the cover is movable in the holder, so that it may be forced more or less into the holder in one or more locations in response to pressure of the shoe on the shoe support to

facilitate the conformity of the support to the contour of the shoe, and as the pressure increases its marginal portion is clamped firmly between the container and the walls of the holder so that the cover is securely held in place. In accordance with a further feature also a portion of the container is confined by a substantially rigid member which is slidingly movable inwardly and outwardly between the container and the holder, this member, as illustrated, being arranged to overlap a portion of the container which projects toward the shoe beyond that wall of the holder which is farthest from the end of the toe of the shoe, this wall of the container being recessed to provide clearance for the shoe. As illustrated, the rigid member comprises a plate which is fastened to a portion of the flexible cover.

The novel features of the invention will now be more particularly described by reference to the accompanying drawing and pointed out in the claims.

In the drawing,

Fig. 1 shows in vertical section a forepart support or toe rest in which the invention is embodied, arranged to serve as a portion of a bed-lasting machine; and

Fig. 2 shows the shoe support in elevation, as viewed from the right of Fig. 1, a portion of the structure being broken away.

As illustrated, the forepart support or toe rest comprises a fluid container 10 mounted in a cup-shaped metal holder 12 which is supported on the head 14 of a stem 16 whereby the toe rest is positioned in the lasting machine. It will be understood that the toe rest supports the forepart of the shoe against heavy downward pressure applied to the marginal portion of the upper over the insole by wipers 18 located over a toe band 20 which clamps the upper around the toe near the edge of the shoe bottom. The container 10 is made of rubber and, as illustrated, has no reinforcing material forming a part thereof, the container therefore being very flexible and readily conformable to the contour of the shoe. In its bottom portion the container has an opening 22, and through this opening and a corresponding opening in the bottom

of the holder 12 extends a short tube 24 projecting from a plate 26 which overlaps the lower wall of the container and serves to clamp this wall against the bottom of the holder 12. The tube 24 is threaded and has a nut 28 thereon which clamps a collar 30 against the bottom of the holder. It will be seen that by this means the flexible container is securely clamped in the holder. The 10 container, as illustrated, is filled with liquid, preferably water, which because of the fact that it is non-compressible, affords a firm support for the shoe while permitting the container to conform itself readily to the contour of the shoe. A threaded plug 32 closes the opening in the tube 24 and confines the liquid. The collar 30 is fitted within a recess in the head 14 and is confined by a pin 34 which is mounted in the head and lies partly 20 in a groove 36 formed in the periphery of the collar, the groove being large enough to permit some turning movement of the holder 12 so that the toe rest may adjust itself to right and left shoes. It will be evident that when 25 the pin 34 is withdrawn the holder 12 and the parts mounted thereon may be detached as a unit.

It will be observed that the side walls of the holder 12 inclose portions only of the side walls of the flexible container 10, a substantial portion of the container projecting from the holder to permit it to conform to the contour of the shoe without danger of contact of the shoe with the holder. In order to confine the projecting portion of the container against excessive expansion in any location under pressure of the shoe thereon, there is provided a flexible cover 38 which is fitted to serve as a cap inclosing the top and portions 40 of the side walls of the container, this cap being preferably formed of non-elastic material, such as leather, and serving additionally to protect the rubber container from excessive wear. Preferably the cover is 45 loosely mounted on the container, i. e., without being fastened to it. It will be seen that the container is normally somewhat smaller than the interior of the holder, so that a space is provided into which the marginal portion 50 of the cover 38 projects heightwise of the shoe and where it is clamped against the holder by pressure of the fluid in the container when the shoe presses on the support. The marginal portion of the cover, which terminates short of the bottom of the holder, is 55 slidably movable inwardly and outwardly between the container and the walls of the holder, and it will be understood that as pressure is applied on the top of the container the 60 marginal portion of the cover may slide more or less into the holder in one or more locations to facilitate conformity of the cover and the container to the contour of the shoe. As the pressure increases the marginal portion of the 65 cover is clamped so firmly between the con-

tainer and the holder by the pressure of the fluid as to maintain the cover securely in place over the upper portion of the container and thus to prevent any excessive expansion of portions of the container located between the holder and the shoe. 70

It will be observed that the wall of the holder 12 which is located on the side farthest from the end of the toe of the shoe is recessed, as indicated at 40, to insure enough clearance for that portion of the shoe which is over it. To assist in preventing any undue expansion of the flexible container between this wall and the shoe, there is further provided a substantially rigid metal plate 42 which overlaps the container in this location and terminates far enough from the shoe to avoid contact therewith. This plate is fastened by rivets 44 to the cover 38, and is 80 slidably movable with the marginal portion of the cover inwardly and outwardly between the container and the wall of the holder. It will be understood that in response to pressure of the shoe on the shoe support the plate 42 and the portion of the cover 38 to which it is attached are first moved more or less into the holder as the container and the cover conform themselves to the contour of the shoe, after which the plate and the attached portion of the cover are firmly 85 clamped against the wall of the holder by the pressure of the fluid. 90

Having described the invention, what I claim as new and desire to secure by Letters Patent of the United States is:

1. A shoe support comprising a flexible fluid container constructed and arranged to support a shoe at the top of the forepart, a holder inclosing a portion of said fluid container, and a flexible cover arranged to lie between the container and the shoe with its marginal portion extending heightwise of the shoe into the holder in position to be clamped against the holder by pressure of the fluid in the container, said marginal portion being movable in the holder heightwise of the shoe relatively to the container. 105

2. A shoe support comprising an elastic fluid container constructed and arranged to support a shoe at the top of the forepart; a holder inclosing a portion of said fluid container, and a substantially non-elastic flexible cover loosely mounted over the container with its marginal portion extending heightwise of the shoe into the holder a portion only of the distance that the container extends in position to be clamped against the holder by pressure of the fluid in the container. 115

3. A shoe support comprising a flexible fluid container constructed and arranged to support a shoe at the top of the forepart, a holder inclosing a portion of said fluid container, and a flexible cover mounted over the container and separate therefrom with 120 125 130

its marginal portion extending heightwise of the shoe into the holder and arranged to be forced farther into the holder in response to pressure of the shoe on the shoe support and 5 then to be clamped against the holder by increasing pressure of the fluid in the container.

4. A shoe support comprising a flexible fluid container constructed and arranged to 10 support a shoe at the top of the forepart, a holder inclosing portions of the sides of said fluid container, and a cap of flexible material formed to inclose the top and the remaining portions of the sides of the container, said cap being loosely mounted over the container with its marginal portion terminating short of the bottom of the holder in position to be clamped against the holder by pressure of the fluid in the container. 15

20 5. A shoe support comprising a rubber fluid container constructed and arranged to support a shoe at the top of the forepart, a holder inclosing portions of the sides of said fluid container, and a cap of substantially non-elastic flexible material inclosing the top and the remaining portions of the sides of the container, the marginal portion of said cap being movable relatively to the container inwardly and outwardly between the container and the side walls of the holder. 25

30 6. A shoe support comprising a rubber receptacle containing liquid and formed and arranged to support a shoe at the top of the forepart, a holder having rigid walls inclosing portions of the sides of said rubber receptacle, and a leather cap separate from said receptacle and fitted to inclose the top and portions of the sides of the receptacle, the marginal portion of said leather cap extending into said holder and being movable relatively to the receptacle inwardly and outwardly between the receptacle and the walls of the holder. 35

40 7. A shoe support comprising a flexible fluid container constructed and arranged to support a shoe at the top of the forepart, a holder in which said fluid container is mounted, a portion of the container being arranged to extend heightwise of the shoe outside of the holder, and a substantially rigid member arranged to confine said outwardly extending portion of the container, said member extending into the holder and being movable inwardly and outwardly between the container and the holder. 45

50 8. A shoe support comprising a flexible fluid container constructed and arranged to support a shoe at the top of the forepart, a holder in which said fluid container is mounted, said holder on the side farthest from the end of the toe of the shoe having a wall recessed to provide clearance for the shoe and beyond which a portion of the container extends toward the shoe, and a plate arranged 55 to overlap the container in that location, said

plate extending into the holder and being movable inwardly and outwardly between the container and the wall of the holder.

9. A shoe support comprising a flexible fluid container constructed and arranged to support a shoe at the top of the forepart, a holder in which said fluid container is mounted, a flexible cover extending over the container outside of the holder, and a substantially rigid member attached to said cover and overlapping a portion of the container, said member extending into the holder and being movable inwardly and outwardly between the container and the holder. 70

10. A shoe support comprising a flexible fluid container constructed and arranged to support a shoe at the top of the forepart, a holder inclosing portions of the sides of said fluid container, a cap of flexible material formed to inclose the top and the remaining portions of the sides of the container, and a plate attached to said cap and overlapping a portion of the container outside of the holder, said plate extending into the holder and being movable inwardly and outwardly between the container and the holder. 80

11. A shoe support comprising a rubber receptacle containing liquid and formed and arranged to support a shoe at the top of the forepart, a holder having rigid walls inclosing portions of the sides of said rubber receptacle, a flexible cap of substantially non-elastic material fitted to inclose the top and portions of the sides of the receptacle, the marginal portion of said cap extending into the holder and being movable farther into the holder in response to pressure of the shoe on the shoe support, and a plate attached to the marginal portion of said cap and overlapping a portion of the receptacle outside of the holder, said plate being movable into the holder with that portion of the cap to which it is attached. 90

12. A shoe support comprising a flexible fluid container constructed and arranged to support a shoe at the top of the forepart, a holder inclosing a portion of said container and having a wall on the side farthest from the end of the toe of the shoe recessed to provide clearance for the shoe, a cap of flexible material inclosing the top of the fluid container and extending into the holder, and a plate attached to said cap and overlapping a portion of the container extending toward the shoe beyond the recessed wall of the holder, said plate and the portion of the cap to which it is attached being movable inwardly and outwardly between the container and said wall. 100

13. In testimony whereof I have signed my name to this specification. 110
